(57) **CLAIM**

The ornamental design for earphone, as shown and described.

DESCRIPTION

FIG. 1 is a front elevational view thereof;
FIG. 2 is a rear elevational view thereof;
FIG. 3 is a left side view thereof;
FIG. 4 is a right side view thereof;
FIG. 5 is a top plan view thereof.
FIG. 6 is a bottom plan view thereof; and,
FIG. 7 is a perspective view of a earphone showing my new design.
The broken lines depict portions of the earphone that form no part of the claimed design.
